DESIGN FOR A CONTROL UNIT FOR ELECTRICAL APPARATUS

John Vassos, New Canaan, Conn., assignor to
Radio Corporation of America, a corporation
of Delaware

Application May 11, 1937, Serial No. 69,290

Term of patent 7 years

To all whom it may concern:

Be it known that I, John Vassos, a citizen of the United States and a resident of New Canaan, in the county of Fairfield and State of Connecticut, have invented a new, original, and ornamental Design for a Control Unit for Electrical Apparatus, of which the following is a specification, reference being had to the accompanying drawing, forming a part thereof.

The figure is a perspective view of a control unit for electrical apparatus embodying my new design.

I claim:

The ornamental design for a control unit for electrical apparatus substantially as shown.

JOHN VASSOS.
